UNITED STATES PATENT OFFICE.

WILLIAM WILBRAHAM, OF CHICAGO, ILLINOIS.

CEILING-ROSETTE FOR DROP ELECTRIC LAMPS.

No. 921,038.

Specification of Letters Patent.

Patented May 11, 1909.

Application filed July 14, 1908. Serial No. 443,540.

To all whom it may concern:

Be it known that I, WILLIAM WILBRAHAM, a citizen of the United States, residing at Chicago, in the county of Cook and State of Illinois, have invented a new and useful Ceiling-Rosette for Drop Electric Lamps, of which the following is a specification.

My invention relates to rosettes that are used to connect the electric lamp cord to the ceiling in the wiring work for lighting buildings and has for its object to simplify the construction work, save cost and to produce a neat rosette and one that will be safer from a fire standpoint than the rosettes heretofore used.

Reference will be had to the accompanying drawing in which,

Figure 1 is a top plan view of my invention and Fig. 2 is a side sectional view. Fig. 20 3 is a side elevation.

In the drawing A indicates the rosette which may be any suitable block of porcelain or other suitable material made in any ornamental shape but I prefer to use the shape here shown. In this block A there is a cavity B into which there extends a side cavity C. As an extension of cavity B there is a smaller cavity D extended through the block and provided with a shoulder E adapted to fit the under side of a screwhead F of a screw G, which extends upward into an expansion nut H set into a concrete ceiling I, but the screw G may be used to secure the rosette to any ceiling. A rim J on the edge 30 35 of the cavity K causes the rosette to bear on the outer edges of the rosette and bear firmly on the ceiling without rocking which is a desideratum.

The electric lamp cord or wires L come 40 along the ceiling and are passed through the hole or aperture C into the cavity B and then drop downward to the lamp M thus allowing the simplest construction possible.

In all other rosettes of this class heretofore 45 used it requires two or more screws to hold them upward to the ceiling and in concrete work this is expensive and also it does not make as good a job, and in other instances a wooden block is first screwed to the ceiling 50 permanently and then the rosette is detachably fixed thereto which is made necessary to properly fix the wires to the rosette. Further with two or more pieces to the rosette

it affords an abode for insects that is objectionable and they are not as safe from a fire 55 standpoint.

What I claim is,

1. A rosette consisting of a block of insulating material having an axial passage extending through the block and a lateral perforation in the wall of the passage, said passage being provided with an internal shoulder above the lateral perforation to receive the head of an attaching screw inserted in the passage; whereby the block may be secured 60 to a wall by such screw and a conductor may be passed through the perforation and thence downward in the open portion of the passage, substantially as set forth.

2. A rosette consisting of a single piece of insulating material having a marginal rim to bear against the ceiling, having also an axial screw receiving passage extending from top to bottom and enlarged below to permit the screw head to enter the block to some distance, and further having the lateral wall of the enlarged portion of said passage provided with a perforation for the passage of an electrical conductor, substantially as set forth.

3. A rosette of the class described composed of a one piece block having a vertical central opening extending entirely through the block, said opening being larger from the bottom upward to the interior of the block 75 and then restricted to form a shoulder for a screwhead the balance of the opening being the proper size for a screw body; and further having a horizontal or lateral opening 80 in the side of the block extending into the 85 larger portion of the opening below the screw head shoulder; and also having a bearing rim on the outer periphery of the block adapted to bear on the ceiling, combined with a screw and an expansion nut for fastening the rosette to the ceiling and an electric 90 lamp cord extending through the horizontal opening and down through the enlarged portion of the vertical opening as described.

In witness whereof I have hereunto signed 100 my name in the presence of two subscribing witnesses on this 9th day of July, 1908.

WILLIAM WILBRAHAM.
